UNITED STATES PATENT OFFICE

112,088

DESIGN FOR A SIGNAL DEVICE

Lloyd Rittenhouse, Honeoye Falls, and Sidney M. Crossett, Rochester, N. Y., assignors to The A. E. Rittenhouse Co., Inc., Honeoye Falls, N. Y., a corporation of New York

Application July 20, 1938, Serial No. 78,605

Term of patent 14 years

To all whom it may concern:

Be it known that we, Lloyd Rittenhouse and Sidney M. Crossett, both citizens of the United States of America and residing at Honeoye Falls and Rochester, respectively, in the county of Monroe and State of New York, have invented a new, original, and ornamental Design for Signal Device, of which the following is a specification, reference being had to the accompanying drawing, forming a part thereof.

In the drawings:

Fig. 1 is a view in front elevation of a signal device showing our new design;

Fig. 2 is a side elevation of the same;

Fig. 3 is a top plan view, and

Fig. 4 is an enlarged perspective view of the housing thereof.

We claim:

The ornamental design for a signal device, as shown.
